UNITED STATES PATENT OFFICE.

SAMUEL J. HERMAN, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER-CLEANER CONSTRUCTION.

Application filed December 2, 1918, Serial No. 264,933. Renewed December 30, 1925.

This invention relates to boiler cleaners and refers more particularly to boiler cleaners of the type in which a rotatable blower unit carries nozzles through which steam or other cleaning substance is discharged against the tubes or other surfaces to be cleaned.

Among the objects of the invention is the provision of a rotatable blower pipe provided with discharge orifices and slidable between two limiting positions of use. The invention further resides in the provision of suitable means to retain the slidable blower pipe in one of its limiting positions.

Among the further objects of the invention are to provide an improved construction and operating mechanism whereby the tube can be shifted to various positions; to provide an improved arrangement of blower units for boilers of the Wickes or similar types; and in general to provide a new and improved boiler cleaner construction of the character above referred to.

In certain types of boilers, of which the Wickes is an example, the rows of tubes are separated by a space interval too small to admit a blower tube of a capacity sufficient to clean all of the adjacent boiler tubes. As a solution for this difficulty, the invention provides for a longitudinal adjustment of the blower tube, whereby it has two positions of discharge in each of which it acts upon half of the adjacent boiler tubes.

In the drawings:

Figure 1 is a vertical sectional view of a boiler of the Wickes type to which my invention is applied;

Figure 2 is a view of the same in cross-section on line 2—2 of Figure 1;

Figure 3 is an enlarged axial section through one of the blower units, showing the mounting thereof in the boiler wall;

Figure 4 is a top view of the same;

Figure 5 is an end view of the same;

Figure 6 is a cross-section on line 6—6 of Figure 4.

Describing in detail the construction shown in the drawings and referring first to the general arrangement of parts shown in Figure 1, A designates a boiler of the Wickes type having a plurality of tubes B extending between the upper and lower drums C and C', there being a vertical baf-

fe C² arranged to compel the gases from the furnace chamber D to pass upwardly at one side of said baffle and downwardly at the other side thereof before reaching the flue outlet. For cleaning the soot from the outer surface of the tubes B there are employed blower units E, the construction and arrangement of which form the material features of my invention.

Each of the blower pipes E is provided with a plurality of nozzles F through which steam is discharged against the outer surfaces of the boiler tubes B, and as shown in Figures 3, 4, and 5, means are provided for shifting the pipes E longitudinally so as to adapt them for operation in either of two positions. While various mechanisms may be employed for this purpose, I preferably employ a construction utilizing the steam pressure to effect movement of the pipe to its more advanced position, and maintaining the pipe normally retracted by means of a suitable coiled spring. Describing now this construction, G is a tubular casing extending through the boiler wall, said casing having an interior annular flange G' at its inner end and having its outer end projecting beyond the boiler wall and screw-threaded, as indicated at G², to engage one of the aligned openings of a T-fitting H. The other aligned opening of said fitting is engaged by a plug H' having an annular flange H² bearing against an exterior face of the fitting. The third orifice H³ of the fitting opens downwardly to engage a steam inlet pipe J. Within the casing G there is slidably mounted a tubular plunger K formed with a plurality of steam inlet ports K' and having its forward end inferiorly flanged, as indicated at L, and screw threaded to engage the blower pipe E. Externally the plunger K is formed with an annular shoulder K² which is engageable with the flange G' to limit forward movement of the plunger and blower pipe. The rear portion of the plunger is of reduced diameter for engagement with a stem M, which extends slidably through the plug H' and also centrally through a sleeve M' rigidly secured to said plug, as indicated at M². Said stem carries upon its rear end a handle O, by means of which a rocking motion may be communicated to the stem and thereby

through the plunger K to the blower pipe E for the purpose of varying the direction of the jets of steam discharged from said blower pipe. Adjacent said handle a washer P is mounted upon the stem and a coiled spring P' is arranged between said washer and the plug H' for holding the slideable parts normally rearwardly retracted. In Figure 3 there is illustrated in dash lines the position occupied by the handle O when the sliding parts are in their advanced positions. The bearing of the stem M in the plug H' is safeguarded against leakage of steam by packing Q retained in position by a gland Q'. To permit movement of the handle O between the positions indicated in full and in dash lines in Figure 3 the sleeve M' is formed with a longitudinally-extending slot R, the forward end of which communicates with a circumferentially-extending slot R', whereby the necessary rocking movement of the handle member in its forward position is permitted, the permissible extent of said rocking movement being limited through contact of the handle with the slot extremities. To similarly limit rocking of the handle when in its retracted position, the top portion of the sleeve M at its rear end is cut away so as to form diametrically opposed shoulders S, constituting stops for the rocking motion of the handle. When steam is admitted to the pipe E from the pipe J, the plunger K is subjected to a considerable pressure, tending to shift it to its advanced position and to resist this force when the pipe is being used in its retracted position, a latch member T is hingedly connected to the sleeve M' at the rear end of said sleeve and is adapted to be swung across the slot R to form an abutment for the handle O as it is being rocked back and forth in its retracted position. When it is desired to advance the blower pipe to its forward working position, it is necessary simply to swing the latch member T to its raised position, as indicated in dash lines in Figure 5, then shift the handle O into registration with the slot R, whereupon the steam pressure acting on the plunger will carry the sliding parts forward, overcoming the spring P' and shifting the handle to its position, indicated in dash lines in Figure 3. Whenever steam pressure is cut off from the blower pipe, the spring P' will automatically return the sliding parts to their retracted positions provided that the handle O is registered with the slot R. The stroke of the sliding parts is preferably equal to the distance between two of the rows of boiler tubes transverse to the pipe E so that the nozzles F of said pipe will be registered with alternating rows of the boiler tubes in the two respective working positions thereof.

65 Another feature of the invention resides

in the construction of the unit E, the details of which are shown in Figures 3, 4 and 6. The nozzles F are preferably arranged to project inwardly toward the center of the unit or pipe E instead of being arranged exteriorly of the unit as heretofore. Each nozzle is provided with an outwardly-extending projection T' which passes through a corresponding aperture in the pipe and preferably has a drive fit therein. Heretofore, it has been customary to weld the entire circumference or contacting portions of the nozzle and the surrounding wall of the pipe, but in the present construction I avoid the necessity of such connection by providing the nozzle F with a segmental flange T² which fits snugly against the interior surface of the pipe E and is secured thereto preferably by spot welds T³ located at two or more points around the segment.

The described construction of the nozzle and manner of connecting it to the blower unit or pipe not only reduces the cost of manufacture and assembly, but gives a very rigid connection and one which, because of the wide contacting area between the flange T² and the inner wall of the pipe, furnishes a reinforcement at the nozzle opening. I do not, however, desire to limit the invention to the particular shape of the nozzle shown, nor to the other details of construction, except as ultimately set forth in the claims.

What I claim as my invention is:

1. In a boiler cleaner, the combination with a rotatable blower pipe having discharge orifices, of a mounting slidably and rotatably carrying said pipe and adapted to admit steam thereto, a stem projecting rearwardly from said pipe extending exteriorly of said mounting, a sleeve enclosing said stem carried by said mounting, said sleeve being formed with intersecting longitudinal and circumferential slots, and a crank carried by said stem whereby the blower pipe may be rotated, movable in the longitudinal slot during sliding of the blower pipe, and in the circumferential slot during rotation of said pipe.
2. In a boiler cleaner the combination with a rotatable blower pipe having discharge orifices of a mounting in which said pipe is slidably and rotatably carried, a stem projecting rearwardly from said pipe exteriorly of said mounting, a sleeve surrounding said stem projecting rearwardly from the mounting, means carried by said stem whereby the blower pipe may be rotated said means being limited in its rotation by said sleeve and a latch member on the sleeve engageable by said means to maintain the blower pipe normally retracted.
3. In a boiler cleaner, the combination with a blower pipe having discharge openings, of a mounting in which said pipe is

rotatably and slidably carried, a stem rearwardly projecting from said pipe and extending exteriorly of said mounting, a sleeve surrounding said stem carried by the mounting, said sleeve being longitudinally and circumferentially slotted, a crank upon said stem whereby the blower pipe may be rotated movable in the longitudinal slot of said sleeve during projecting or retraction of the blower pipe and angularly movable in the circumferential slot in the projected position of the blower pipe and a latch member pivoted upon said sleeve normally bridging the longitudinal slot thereof, engageable by said crank to thereby maintain the blower pipe retracted.

4. The combination with a blower pipe slidable between two limiting positions of use, of means utilizing pressure of the cleaning fluid supplied to said pipe to urge said pipe to one of said limiting positions, and a latch member adjustable to and from a posi-

tion retaining said blower pipe in its other limiting position.

5. The combination with a mounting having an inlet for a cleaning fluid, of a blower pipe rotatable in said mounting and slideable therein between two limiting positions of use, a rearward extension from said mounting, means utilizing pressure of the cleaning fluid to urge said pipe to one of said limiting positions, and a latch member carried by said extension and pivotally adjustable thereupon to and from a position retaining said blower pipe in its other limiting position.

6. The combination with a blower pipe slideable between two limiting positions of use, of means tending to urge the blower pipe from one limiting position to the other, and a latch mechanism for retaining said blower pipe in the said other limiting position.

In testimony whereof I affix my signature.
SAMUEL J. HERMAN.
